ABSTRACT OF THE DISCLOSURE

A computing circuit for processing input complementary trigonometric functions defined by amplitude and angular data to derive an indication of the angular data. Complementary trigonometric functions of a trail angle are generated and products formed between these functions and the input trigonometric functions, the products being combined to derive a representation of the amplitude data and the representation combined with the products to derive an indication of the angular data.

This application is a division of applicant's prior pending application Ser. No. 435,149, filed Feb. 25, 1965, now Pat. 3,366,804, and also includes subject matter described in prior copending application Ser. No. 353,558, filed Mar. 20, 1964, entitled Data Processing of which applicant is a co-inventor.

This invention relates to switching techniques employed in bridge circuits and to solid state switching of such arrangements.

Although solid state switching offers certain advantages over electro-mechanical arrangements, there are many applications where the solid state switch, although otherwise acceptable in terms of complexity, cost, and size, does not possess the requisite performance specifications to meet accuracy requirements.

For example, the dynamic impedance of a solid state diode employed as a switching element may be several ohms and may be as high as several hundred ohms. These impedances may be wholly unacceptable in many applications.

Although there are means for reducing this dynamic impedance, these means frequently result in an increase in cost and complexity to the point where it is more feasible to employ electro-mechanical switching arrangements.

It is accordingly one object of the invention to provide an improved solid state switching arrangement for bridge circuits characterized by an improvement in accuracy which is attained without a corresponding increase in size or complexity. It is a further object of the invention to provide improved control arrangements employing such solid state switches in combination with bridge circuits for effecting improvements in various data processing functions including logic operations and basic computations.

Other objects and advantages of the invention will be set forth in part hereinafter and in part will be obvious herefrom or may be learned by practice with the invention, the same being realized and attained by means of the instrumentalities, combinations and improvements herein shown, described and claimed.

Serving to illustrate exemplary embodiments of the invention are the drawings of which:

FIG. 1 is a schematic diagram of a switching arrangement according to the invention;

FIG. 2 is a schematic wiring diagram of a prior art diode switching circuit;

FIG. 3 is a schematic wiring diagram of an inductive divider controlled with the aid of switching devices such as those illustrated in FIG. 1;

FIG. 4 is a schematic diagram illustrating the switching arrangement of FIG. 1 in a combination providing an inversion operation;

FIG. 5 is a schematic diagram illustrating the switching techniques of FIG. 1 in a circuit for converting digital inputs to analogue outputs; and

FIG. 6 is a schematic diagram of a resolver bridge employing switching techniques according to the invention.

For the purpose of contrast, initial reference is to the circuit of FIG. 2 wherein there is illustrated a solid state diode bridge circuit employed for switching in accordance with prior art techniques.

The diode bridge is constituted with one branch of serially interconnected diodes D_1 and D_2 and another, shunt branch, formed of serially connected diodes D_3 and D_4 . The cathode side of the bridge is connected via a resistor R_A to switching voltage E_A ; similarly, the anode side of the bridge is connected via a resistance R_B to the switching voltage E_B .

The controlled or switched circuit includes a source 25 of potential e having one side connected to the common terminal, illustratively ground, and its other terminal connected to the junction of D_1 and D_2 . The controlled circuit further includes an output or load circuit U which may be a utilization device, e.g., some circuit in a signal 30 transmission path. Circuit U has one end connected to the junction of diodes D_3 and D_4 and its other terminal returned to the return or ground terminal.

In operation, voltages E_A , E_B of the proper amplitude and opposite polarity are applied to the switching terminals 35 causing the diodes D_1 , D_2 , D_3 and D_4 to become forwardly biased. As a result conduction is established between the source e and the output circuit U thereby effecting the switching action.

A practical circuit of the type shown in FIG. 2 has 40 a number of significant limitations. For one, the resistances R_A and R_B act as a load on the source e . The dynamic impedance of the diodes varies inversely with the diode current and since the diodes are effectively in series with the source and output circuit, it becomes necessary 45 to keep the diode dynamic impedance at a sufficiently low value. To do this it is necessary to maintain a relatively high current through the diodes thereby necessitating a minimization of the size of R_A and R_B . This, however, as noted above, complicates the loading problem. Hence, 50 the circuit requires a compromise of diverging criteria with an attendant limitation on performance.

Certain of the disadvantages of FIG. 2 have been 55 overcome by circuits according to the invention such as illustrated in FIG. 1. The main switching arrangement therein illustrated includes a diode bridge having one branch comprising serially interconnected diodes D_A and D_B . The junction of these two diodes is connected to the common ground terminal. A parallel branch comprises serially interconnected diodes D_{1A} and D_{1B} . The junction of D_{1A} and D_{1B} is connected to the circuit to be controlled, U_1 , as well as to the switched voltage source e connected in series with U_1 . In practice and in certain 60 applications it may be preferable to interchange the relative positions of source e and switched circuit U_1 . In either 65 configuration, the switching bridge of FIG. 2 provides the common or reference terminal on one side of the bridge (schematically indicated with the ground terminal) and the circuit to be switched along with the source, on the other side of the bridge. Hence, when the bridge is 70 switched on, the ground connection is supplied to the controlled circuit causing current flow therein. The ground

connection may be by way of an impedance small enough to preclude deterioration in accuracy or interference with the control circuit. In view of this arrangement, the loading effect on the source provided by the resistors in the switch control circuit is eliminated. Furthermore, the forward switching voltage can be low in the circuit of FIG. 1 whereas in the prior art arrangement it must exceed the peak value of the signal source e .

The anode side of the switching bridge in FIG. 1 is connected to a first switching voltage $-E_1$ via a resistance R_{1B} . The anode side is also connected to a second switching voltage $+E_2$ via the series combination of resistance R_{2B} and the collector-emitter circuit of a transistor driver Q_B . On the cathode side of the diode bridge there is an analogous connection to a switching voltage $+E_1$ via a resistance R_{1A} and to a second switching voltage $-E_2$ via the series combination of resistance R_{2A} and the collector-emitter circuit of a driver stage Q_A .

The switching voltages $+E_1$ and $-E_1$ are operative to back-bias the diode bridge to a sufficient degree to prevent conduction except under the conditions described herein-after. In contrast with the arrangement of FIG. 2, the bridge is supplied with separate switching voltages $+E_2$ and $-E_2$ which are operative when applied to the bridge to cause conduction with a resultant switching of the output circuit. The voltages $\pm E_2$ may be relatively small compared with the amplitude of E_1 and in an illustrative application E_2 may be in the order of three volts while E_1 is thirty volts.

The base of Q_A is connected via a resistance R_{3A} and a diode D_4 to an input terminal I_{1A} . Similarly, the base of Q_B is connected via the series combination of R_{3B} and D_7 to terminal I_{1B} . With the circuit as thus far described, the application of a potential at I_{1A} which is sufficient to forwardly bias Q_A will cause the saturation of Q_A and the resultant connection of the *on* voltage, $-E_2$, to the diode bridge via resistance R_{2A} . A similar voltage of opposite polarity applied to terminal I_{1B} causes Q_B to be switched *on* with the result that $+E_2$ is applied to the anode side of the bridge via R_{2B} . When these actions are accomplished, the bridge is rendered conductive, causing the switching circuit U_1 , e , to be grounded and therefore completed.

It should be noted here that Q_A and Q_B are transistors of complementary types and are biased by $-E_2$ and $+E_2$ such that a voltage positive with respect to $-E_2$ (e.g., a ground or voltage of zero amplitude) can switch *on* Q_A while a voltage negative relative to $+E_2$, which again can be the ground potential, can cause the switching *on* of Q_B . Alternatively, by proper selection of bias, base resistances and switching voltages, the switching levels for the A and B circuits can be made different to adapt the arrangement to logic operations employing multi-switching levels.

Since the forward switching voltage $\pm E_2$ may be comparatively low and since the resistances R_{2A} and R_{2B} do not load the switched circuit and thus may be of low value, there is less power required for switching a given amount of output power.

The circuit of FIG. 1 is amenable to a latching or memory type characteristic and to this end cross coupling circuits G_A and G_B may be employed, the former connecting the collector of Q_A to input terminal I_{1B} via a switch S_a and the latter connecting the collector of Q_B to input terminal I_{1A} via a switch S_b .

Assuming both switches S_a , S_b are closed, the circuit of FIG. 1 will latch *on* if a ground or other suitable potential is applied to either of the input terminals I_a or I_b . In the absence of such a potential the circuit is maintained *off* because the collector of Q_B is negative relative to the potential $-E_2$ while the collector of Q_A is more positive than the potential $+E_2$. Once the circuit has been switched *on* (and assuming of course that switches S_a and S_b are closed), the circuit will stay in a conductive state even after the switching voltage is re-

moved from terminal I_{1a} or I_{1b} . This results from the relatively negative potential which is coupled from the collector of Q_A to the base of Q_B and because of the relatively positive potential which is coupled from the collector of Q_B to the base of Q_A .

In certain applications it is desirable to have the capability of effecting switching at different control levels. This is accomplished in FIG. 1 by simply opening switch S_a or S_b . When this is done the latching characteristic is eliminated but a choice of switching levels is made available. For example, and assuming that switch S_a is open, a relatively negative potential applied at input terminal I_{1B} causes Q_B to be switched *on*. When this occurs a forward biasing potential is coupled from the collector of Q_B to the base of Q_A so that the entire bridge is switched *on*. If on the other hand S_a is closed and S_b is opened, a relatively positive potential at terminal I_{1a} will switch the bridge into conduction.

The circuit of FIG. 1 is also particularly adapted to supply a monitoring signal or an auxiliary signal and this is advantageously attained from any one of several points including the junction A of FIG. 1 to which is connected an auxiliary output terminal M_1 useful for monitoring or other purposes.

Because of its performance characteristics and in view of the fact that it acts to complete a circuit to ground, the embodiment of FIG. 1 is also adapted to provide multi-pole operation. This is readily accomplished by connecting additional branches in parallel with the main bridge. Thus, as illustrated, an additional branch comprising serial diodes D_{2A} and D_{2B} may be connected in parallel with the bridge with the junction of D_{2A} and D_{2B} being connected to the switched circuit U_2 and its series source e . Similarly, an additional circuit U_3 and its source e may be switched by connecting the same to the junction in an additional branch comprising serially connected diodes D_{3A} and D_{3B} .

The diodes D_4 and D_7 in the base circuits of Q_A and Q_B , respectively, serve the function of preventing damage to the associated collector-base junction. In addition these diodes may be employed in combination with parallel input diodes to provide logic operations, for example, OR functions. Thus as illustrated in FIG. 1, the input I_{1A} may be paralleled by inputs I_2 and I_3 connected to R_{3A} via respective diodes D_5 and D_6 . The driver sections of FIG. 1 may thus be utilized to provide logic operations, a technique which is frequently not feasible in electro-mechanical relay circuits.

Because of its accuracy, the switching arrangement of FIG. 1 is particularly adapted for use in certain computing operations where high order accuracy is required. However, the switching device according to the invention functions to complete the ground circuit and for this reason its combination with other computation elements in some cases requires certain unique circuit configurations, certain of these arrangements are illustrated in FIGS. 3, 4, 5 and 6.

Illustrated in FIG. 3 is an inductive divider such as used in data processing, e.g., in precision ratiometric measurement of AC voltages. The divider comprises a transformer T_{10} having a plurality of spaced winding taps connected to define individual winding sections, W_1 , W_2 , W_3 , . . . W_{10} . In the illustration, the complete winding is of the decade type and each section has its tap connected to a respective switching circuit S_1 , S_2 , S_3 . . . S_{11} . These switching circuits are as illustrated in FIG. 1 (with the additional switching circuits D_{2A} - D_{2B} and D_{3A} - D_{3B} not utilized). The output terminal of each of the switching circuits S_1 , S_2 . . . S_{11} is connected to ground such that the application of a suitable voltage to the respective control terminal I_{c1} , I_{c2} , I_{c3} . . . I_{c11} , connects the tap associated therewith to ground. This tap grounding action is different from the usual tap selection arrangements found in inductive dividers and to make this action effective, the upper terminal of the

divider is connected to the succeeding circuit OC which may comprise an output or additional interpolating windings on the same or a different core. The input voltage is applied to terminals I_{10} and I_{11} connected across the entire divider.

It may be seen that the closure of any of the switches $S_1, S_2 \dots S_{11}$ by application of an *on* signal at the respective terminal $I_{c1}, I_{c2} \dots I_{c11}$ results in a grounding of the corresponding tap with the result that all sections below that point do not make any contribution to the resultant output which is developed across the taps above that point and which is connected with the output circuit OC. The switches will each have an appropriate one of the cross couplings G_a or G_b conductive so that the appropriate polarity voltage will cause switch *on* while the opposite causes switch *off*. However, with certain logic circuits it may be preferable to employ the switches with their latching characteristic.

For accomplishing inversion functions with the switch of FIG. 1 circuits may be employed such as illustrated in FIG. 4. As seen therein a transformer T_{20} has the two outside terminals of its primary connected to ground via respective switches S_{20} and S_{21} of the type such as shown in FIG. 1 with one switch, e.g., S_{20} , having the cross circuit G_a complete while S_{21} has the opposite coupling G_b completed. The center tap of the primary winding, W_{20} , is connected to the signal source, e , the other terminal which is grounded. The transformer secondary comprises a winding W_{21} having output terminals I_{20} and I_{21} . A signal voltage e_v of selected polarity is applied to the control terminals I_{22}, I_{23} of the switches.

It may be seen that the transformer will execute a phase reversal when the states of switches S_{20} and S_{21} are reversed. Thus, with S_{20} *on* and S_{21} *off*, e.g., as will occur when signal voltage e_v is positive, the output voltage at terminal I_{20} is out of phase with the voltage e . When S_{21} is switched *on* and S_{20} switched *off*, the voltage e and the output voltage at I_{20} are in phase.

The switching circuits according to the invention are adapted to perform certain binary-digital conversion techniques, one of which is illustrated in FIG. 5. The circuit therein converts a digital input applied at terminals B_1, B_2, B_4 and B_8 into a corresponding analogue voltage, e_A , which appears at output terminal I_{31} .

In implementing the foregoing, a voltage e is applied via a terminal I_{30} to the primary winding of a transformer T_{30} . The transformer secondary is tapped and supplies properly weighted proportions of the voltage e to each of the four summing branches of the converter. A first branch comprises the serial combination of resistance R_{31} and switch S_{31} ; this branch is connected to the top of the transformer secondary. Receiving a reduced potential is the similar series branch comprising resistor R_{32} and switching circuit S_{32} . Successively lower potentials are applied to the third and fourth branches comprising R_{34}/S_{34} and R_{38}/S_{38} .

Although proper weighting of the inputs may be accomplished by an appropriate proportioning of the resistors R_{31}, R_{32}, R_{34} and R_{38} , there is an advantage in weighting the voltages prior to application to the respective branches. In this arrangement the resistors R_{31}, R_{32}, R_{34} and R_{38} may be all of the same size so that with their respective stray capacitances, the phase shift in each branch is substantially equal.

The output sides of the branches are all connected together at a summing junction SJ of an amplifier A_{30} . Across the amplifier is feedback resistor R_{39} while the amplifier output is connected to output terminal I_{31} .

The switches S_{31}, S_{32}, S_{34} and S_{38} are controlled according to the digital inputs supplied at respective control terminals B_1, B_2, B_4 and B_8 . By switching the switching circuits *on* individually and in suitable combinations, various net digital states of the amplifier can be established and proportional analogue voltages thereby developed at the output terminal. For example a switching signal on ter-

minals B_1 and B_4 , representing the quantity 10 for example, will cause the respective switches S_{31} and S_{34} to be switched *on*. As a consequence the branches containing R_{31} and R_{34} are connected to the summing junction SJ with the effect that the amplifier has a gain proportional to the illustrated digital input of 10. When B_2 and B_3 are energized, the corresponding branches R_{32} and R_{38} are rendered effective so that the amplifier in effect provides a sum proportional to the digital input (5), i.e., provides a corresponding analogue voltage which appears at the output. It may be noted that the low switching impedance of the switching circuits S_{31}, S_{32}, S_{34} and S_{38} is especially advantageous in the circuit of FIG. 5 where the switch outputs are connected to the virtual ground of the summing junction with their negligible impedances inserted in each of the summing branches in series with the input resistors.

In FIG. 6 there is illustrated a resolver bridge system employing the switching arrangements according to the invention including the phase inversion technique as illustrated in FIG. 4 and the inductive divider switching technique shown in FIG. 3. In general organization the bridge system of FIG. 6 is similar to that disclosed in copending application, Ser. No. 353,558, filed Mar. 20, 1964 Computer Circuits for PROCESSING trigonometric Data, of which the applicant is co-inventor and which is assigned to the assignee of the instant application.

The input of FIG. 6 comprises the resolver voltages e_1 and e_2 , the former representing the sine component and the latter the cosine component. These voltages may initially be in the form of synchro data which are converted to resolver form by way of the converted DC₆₁. Examples of such converters are illustrated and described in the above-mentioned copending application. Alternatively, the data may be of resolver type in origin.

Voltage e_1 is applied to the primary winding of a transformer T_{70} while voltage e_2 is similarly applied to the primary of a transformer T_{60} . The voltages are each applied to the center tap of the respective primary and the outside terminals of both windings are provided with solid state switches such as those described and illustrated in FIG. 1. It may be seen that the primary of each transformer is instrumented to effect phase reversal in accordance with the switching of the switch pairs S_{60}/S_{61} , in the case of T_{60} , and S_{70}/S_{71} in the case of transformer T_{70} . These switches are actuated by electrical signals generated by the bridge adjust, following the reversal techniques described in the aforesaid copending application.

The secondary of transformer T_{60} consists of two separate inductive dividers each tapped to yield values of sine/cosine increments, D , of 10 degrees. It should of course be understood that other increments may be used. Each tap is connected to a respective switch of the type illustrated in FIG. 1 with the switch functioning to ground the respective tap when the switch is rendered conductive by the appropriate control signal. This arrangement is symbolized by the block labeled SC_{61} , one of the switches being schematically indicated in the closed state whereupon its associated tap connection is grounded. A similar arrangement characterizes the switching circuits connected to the winding W_{62} of T_{60} , this being shown schematically by the block labeled SC_{62} .

The switching of the circuits in SC_{61} and SC_{62} are coordinated such that the adjustment of the bridge to an angle α_1 causes that tap to be selected in SC_{61} which yields the sine of α_1 at the output terminal of W_{61} and causes that tap to be selected in SC_{62} which yields at the output terminal of W_{62} the sine of (α_1+D) . Of course it should be borne in mind that the outputs from both windings are multiplied by a voltage related to cosine θ .

A similar arrangement characterizes the two secondary windings W_{71} and W_{72} of transformer T_{70} . The switching in SC_{71} is such that the output includes the factor cosine α while the switching in SC_{72} yields the cosine of $(\alpha+D)$.

The value of D in degrees is the same as the size of each divider increment.

The resultant four outputs are applied to combining means embodied as a transformer T_{65} and a transformer T_{75} . The primary winding W_{65} of transformer T_{65} is energized by the combination of signals appearing at the outputs of windings W_{62} and W_{72} . The primary winding W_{67} of transformer T_{75} is energized by the combination of signals developed at windings W_{61} and W_{71} . This computing operation is similar to that described in the afore-
10 said copending application.

The output signals developed across the secondaries of transformers T_{65} and T_{75} are combined in the manner shown with one terminal of W_{66} and the center tap of W_{68} being connected across an inductive divider D_{60} . The other end terminal of W_{66} and one end terminal of W_{68} are connected together while the other end terminal of W_{68} is connected via a resistance R_{60} to the common switched terminals of a plurality of solid state switches, SC_{65} , each of which is connected to a respective tap on D_{60} . The junction of resistance R_{60} and this common terminal is connected to a null detector which is responsive to the condition of balance or unbalance in the bridge. Divider D_{60} and the associated switches SC_{65} function as an interpolating arrangement for interpolating the relatively coarse adjustment of the bridge at the input dividers T_{60} and T_{70} . The adjustment of switches in SC_{65} is coordinated with the adjustment of the switching networks SC_{61} , SC_{62} , SC_{71} and SC_{72} .
20

The voltage e_a across W_{68} is combined with e across W_{66} . In the illustrated case e_a is subtracted from e_b and the resultant voltage e_r applied to the divider to produce a fraction of e_r , i.e., a net signal ke_r .
30

The output circuit of FIG. 6 is in essence a form of summing circuit such as shown in FIG. 5 in which currents are summed. The current flowing through R_{60} is a function of e_a while the current flowing out of the switch network is a function of ke_r . The summing junction is effectively at a ground potential because of the feedback effect involving the whole bridge.
35

The bridge may be of the automatic type as described in the aforesaid copending application, i.e., with the bridge adjustment controlled by way of feedback from the null detector or with the bridge adjustment effected independently thereof with the null detector employed to provide read-out or storage of that adjustment angle which yields a null. Alternatively the bridge may be completely manual with the null detector isolated from the bridge adjust and read-out circuits.
40

The invention is not limited to the specific mechanisms shown and described since modifications will undoubtedly occur to those skilled in the art. Changes may be made within the scope of the accompanying claims without departing from the spirit and chief advantages of the invention.
50

What is claimed is:

1. A trigonometric bridge for processing first and second complementary input trigonometric functions defined by amplitude and angular data comprising:
55

bridge adjust means for providing first and second complementary adjusting functions;

first and second computing means each having taps and each including switching means, for producing product functions of said input trigonometric functions and said adjusting functions,
60

said first and second computing means being respectively operably connected to and energized by said first and second input trigonometric functions.

said first and second computing means being operably connected to said bridge adjust means for respectively selectively grounding said taps of said first and second computing means by said switching means in accordance with said

first and second adjusting functions for producing as outputs said product functions; interpolating means operably connected to said computing means and responsive to said output product functions for deriving a first signal proportional to said amplitude data; and means operably connected to said interpolating means and to said computing means and responsive to said first signal and to said output product functions for developing an indication of said angular data.
10

2. A bridge according to claim 1 in which said means connected to said interpolating means and said computing means includes null detector means responsive to said interpolating means and having a virtual ground point, and said interpolating means comprise a tapped divider having third switch means coupled between said taps and said virtual ground point.
20

3. A bridge according to claim 1 in which said interpolating means comprise a compensated interpolator.
25

4. A trigonometric bridge for processing first and second complementary input trigonometric functions defined by amplitude data and angular data θ comprising:
bridge adjust means for providing first and second complementary adjusting functions of angular data α ; first and second computing means each having taps and each including switching means, for producing product functions of said input trigonometric functions of θ and said adjusting functions of α ,
30

said first and second computing means being respectively operably connected to and energized by said first and second input trigonometric functions of θ ,

said first and second computing means being operably connected to said bridge adjust means for respectively selectively grounding said taps of said first and second computing means by said switching means in accordance with said first and second adjusting functions of α for producing as output said product functions;

means operably connected to said first and second computing means and responsive to said output product functions for

deriving a first signal which is a function of $(\theta - \alpha)$ and said amplitude data of said functions of θ but is independent of the individual magnitudes of θ and α , and

deriving a second signal which is approximately proportional to said amplitude data; and combining means responsive to said derived signals for computing the value of said derived signals to compute $(\theta - \alpha)$ and thereby obtain an output indicative of θ .
55

5. A bridge as defined in claim 4 in which said combining means include ratio computing means having taps and ground switching means for adjusting said ratio computing means in accordance with a function of $(\theta - \alpha)$.
60

6. A bridge as defined in claim 5 in which said ground switching means comprise diode bridge means; said diode bridge means comprising two diagonal signal junctions, one of which is grounded and the other of which is connected to said respective tap of said ratio computing means, a control circuit interconnecting diagonally opposite control junctions of said diode bridge for turning the bridge on and off, a forward biasing potential source in said control circuit having one terminal connected to ground, and means in said control circuit for effectively connecting said forward biasing source to said diode bridge to turn same on for grounding said tap.
65

7. A bridge as defined in claim 4 in which said first and second computing means comprise trigonometric ratio dividers;
70

said means for deriving said first signal comprise summing means.
75

8. A trigonometric bridge for processing first and second complementary input trigonometric functions defined by amplitude and angular data comprising:

bridge adjust means for providing first and second complementary adjusting functions;

first and second computing means each having taps and each including switching means, for producing product functions of said input trigonometric functions and said adjusting functions,

said first and second computing means being respectively operably connected to and energized by said first and second input trigonometric functions,

said first and second computing means being operably connected to said bridge adjust means for respectively selectively grounding said taps of said first and second computing means by said switching means in accordance with said first and second adjusting functions for producing as outputs said product functions;

interpolating means operably connected to said computing means and responsive to said output product functions for deriving a first signal proportional to said amplitude data;

null detecting means operably connected to said interpolating means and to said computing means and responsive to said output product functions and said first signal for developing an indication of said angular data; and

feedback control means operably connecting said null detecting means and said bridge adjust means for altering said first and second adjusting functions in accordance with said indication.

9. A bridge as defined in claim 8 in which said null detector means has a virtual ground point, and

said interpolating means comprise a tapped divider having third switch means coupled between said taps and said virtual ground point.

10. A bridge as defined in claim 8 in which said tapped computing means each comprise trigonometric inductive dividers tapped to provide a plurality of sine/cosine values corresponding to a set of adjustment angles.

11. A bridge as defined in claim 8 in which said interpolating means comprise a compensated interpolator.

12. A bridge as defined in claim 8 in which said switching means comprise diode bridge means; said diode bridge means comprising two diagonal signal junctions one of which is grounded and the other of which is connected to the respective tap of the respective computing means, a control circuit interconnecting diagonally opposite control junctions of said diode bridge for turning the bridge on and off, a forward biasing potential source in said control circuit having one terminal connected to ground, and means in said control circuit for effectively connecting said forward biasing source to said diode bridge to turn same on for grounding said tap.

13. A trigonometric bridge for processing first and second complementary input trigonometric functions defined by amplitude data and angular data θ comprising:

bridge adjust means for providing first and second complementary adjusting functions of angular data α ;

first and second computing means each having taps and each including switching means, for producing product functions of said input trigonometric functions of θ and said adjusting functions of α .

said first and second computing means being respectively operably connected to and energized by said first and second input trigonometric functions of θ ,

said first and second computing means being operably connected to said bridge adjust means for respectively selectively grounding said taps of said first and second computing means by said switching means in accordance with said first and second adjusting functions of α for producing as outputs said product functions;

means operably connected to said first and second computing means and responsive to said products for deriving a first signal which is a function of $(\theta - \alpha)$ and said amplitude data of said first and second functions of θ but is independent of the individual magnitudes of θ and α ; and deriving a second signal which is approximately proportioned to said amplitude data; and

combining means responsive to said derived signals for computing the value of said derived signals to compute $(\theta - \alpha)$ and thereby obtain an output indicative of θ ; and

feedback control means operably connected to said combining means and said bridge adjust means for altering said first and second adjusting functions of α in accordance with said output.

14. A bridge as defined in claim 13 in which said first and second computing means comprise trigonometric ratio dividers; said means for deriving a first signal comprise summing means; and said combining means are connected to be responsive to said summing means for computing $(\theta - \alpha)$.

15. A bridge as defined in claim 13 in which said combining means include ratio computing means and ground switching means for adjusting said ratio computing means in accordance with a function of $(\theta - \alpha)$ to compute said ratio.

16. A bridge as defined in claim 13 in which said switching means comprise diode bridge means; said diode bridge means comprising two diagonal signal junctions one of which is grounded and the other of which is connected to the respective tap of the respective computing means, a control circuit interconnecting diagonally opposite control junctions of said diode bridge for turning the bridge on and off, a forward biasing potential source in said control circuit having one terminal connected to ground, and means in said control circuit for effectively connecting said forward biasing source to said diode bridge to turn same on for grounding said tap.
